UNITED STATES PATENT OFFICE.

JULIUS T. SENG, OF CHICAGO, ILLINOIS, ASSIGNOR TO THE SENG COMPANY, OF CHICAGO, ILLINOIS, A CORPORATION OF ILLINOIS.

CORNER-LOCK FOR BEDSTEADS.

1,315,341.

Specification of Letters Patent. Patented Sept. 9, 1919.

Application filed March 11, 1916. Serial No. 83,446.

To all whom it may concern:

Be it known that I, JULIUS T. SENG, a citizen of the United States, residing at Chicago, in the county of Cook and State of Illinois, have invented a new and useful Improvement in Corner-Locks for Bedsteads, of which the following is a specification.

This invention relates to improvements in corner-locks for bedsteads; and the principal objects in view are to provide a lock of this character capable of being readily, economically and conveniently struck-up from sheet-steel; capable of receiving and rigidly holding the side and end-rails of the bedstead and utilizing the latter rail as an additional support for the former; and which will include a locking-means for the side-rails that will permit of a reversal of the side-rails and which is operable, if desired, without the employment of tools.

Other though minor objects of the invention will hereinafter appear, and the novel features of the invention will be particularly pointed out in the claims.

Referring to the drawings—

Figure 1 is a side elevation of a corner-lock for bedsteads embodying my invention, the same being shown applied to a corner-post of a wooden bedstead, the end-rail being shown in cross-section and the side-rail in side elevation and broken away;

Fig. 2 shows these parts in vertical cross-section, the section being taken on the line 2—2 of Fig. 1, and the lock removed from the post;

Fig. 3 is a vertical longitudinal sectional view taken on the line 3—3 of Fig. 2; and,

Figs. 4 and 5 are details in plan of the ends of the side and end-rails respectively.

Similar numerals of reference indicate similar parts in all the figures of the drawings.

The lock comprises a box-like socket, the front and bottom of which is preferably open and the top and rear closed, as shown. It may, therefore, be said preferably to comprise the two vertical side-walls 1, the transverse or top-wall 2, connecting the side-walls, and which at its rear may be upwardly bent at a right-angle and perforated, to form the attaching ear 3, and the rear double wall 4. An attaching-screw 5, may be passed through the perforation of the ear 3 and through similar perforations formed at convenient points in the back-

wall, and utilized to secure the socket to the face of the bed-post 6. The corner-lock herein illustrated is adapted for use in connection with a corner-post of a wooden bed, and therefore attaching-screws are employed, but it will be understood that the invention is applicable to corner-locks intended for use in connection with the corner-posts of metal beds, in which instance, the back-wall of the socket may be formed in any of the well-known conventional ways to effect such an attachment, the fastening-means employed for connecting the socket to the corner-post forming no part of my present invention.

The inner wall 1 of the socket, near the upper edge or top-wall 2, and at about its transverse center, may have punched therefrom, a transversely disposed lug 7, which leaves in said wall a correspondingly shaped opening 8. The upper edge of this opening, for a purpose hereinafter apparent, occurs a distance below the adjacent surface of the top-wall corresponding to the thickness of the angular side-rail hereinafter referred to.

The end or cross-rail 9, is formed of angle-iron, as is usual, and comprises the horizontal web 10 and the vertical web 11. These webs are of the same width, and the vertical web is riveted, as at 12, to the lug or ear 7, its companion or horizontal web 10 entering the opening 8 of the socket and extending transversely therein a short distance and immediately below the underside of the top-wall of the socket. In order that the inner end of the vertical web 11 of the end or cross-rail will not interfere with the adjacent attaching-screw or with the locking-means hereinafter described, said inner end may be recessed or cut out, as at 13.

Immediately below the underside of the top-wall of the socket, the inner one of the side-walls 1, may be extended horizontally beyond its companion wall, as at 14, thus producing upper and lower sides forming angular stop-shoulders 15. When the rail is in position within the housing with its horizontal flange or web uppermost, it will be seen that the free edge of the latter abuts against the inner wall of the housing, so that said inner wall may be said to form an abutment therefor. It will be apparent that a complete inner wall, as shown, is unnecessary for this purpose and that any other form of abutment will answer. When the

rail is in this position, that is, with its horizontal flange uppermost, the latter flange near its free edge, will overlap and be supported by the upper shoulder 15, and when 5 the rail is reversed, that is, so its horizontal flange is lowermost, it will underlap the lower shoulder 15 and be bound or clamped upwardly thereagainst by the described locking means.

10 The locking means employed for the side-rail preferably comprises two companion and similarly formed cam-levers 16, mounted and adapted to rock simultaneously upon a transverse pintle 17, secured 15 to the opposite side-walls 1, said cam-levers each being located in close relation to a sidewall. At their upper ends these levers 16 are widened and provided with cam-faces 18, the highest portions of which are in advance of the pintle 17. A cross-piece or bridge 19, serves to connect the cam-arms 16, and, for convenience, the cam-arms and bridge may and preferably are formed of a single piece bent to shape. An opening 20, 20 is formed in the bridge, preferably at one side of the center thereof so as not to interfere with the adjacent attaching-screw 5 (shown by dotted lines Fig. 2). In the opening 20, is a loose fitting adjusting-screw 21, the rear end of which may be 25 rounded, as shown, and seated in a countersink 22, formed in the back-wall of the socket. A nut 23, (see Fig. 3,) is preferably slightly tapered and threaded on the screw 30 21, immediately back of the bridge 19, and, as will be apparent, by manipulating the adjusting-screw, the cam-levers will be rocked upon the pintle and held in any of 35 their adjusted positions, the nut being held 40 against rotation.

The side-rail 24, as usual, is formed of angle-iron, and therefore comprises the horizontal web 25 and the vertical web 26, taking these parts in the positions they are 45 shown in the figures of the drawings. The socket is preferably made slightly narrower than the webs 25 and 26 of the side-rail, so that, in order for the rail to enter the socket, said webs are slightly reduced transversely, 50 as at 27, at their ends and for a distance corresponding with the length of the socket, thus leaving the webs beyond the socket with lateral angular shoulders 28, which, when the side-rail is in position, overlap or 55 underlap as the case may be, the stop-shoulder 15 adjacent thereto.

In order to assemble the side-rail with the socket, the adjusting-screw 21 is first loosened so as to permit the cams to rock forward a sufficient distance to admit the end 60 of the side-rail. When in position, assuming the side rail to be as shown in the figures of the drawings, the upper or horizontal web 25 will approximately fit between the two 65 vertical side-walls of the socket and the

squared abutting-end of the rail will abut against the back-wall 4 thereof; also the shoulder 28 of the web 25, will lie across and be supported by the shoulder 15 of the socket, the interlocking of these two shoulders serving to resist torsional strain of the rail. The screw is now run down upon the nut 23, thus forcing the upper ends of the cam-arms rearwardly and causing the outer cam to bind against the under edge of the 70 vertical web of the angle-iron of the side-rail and force the latter tightly upward against the underside of the top-wall of the socket, whereby, as will be apparent, the side-rail is rigidly and securely locked in 80 position. For the purpose of operating the adjusting-screw 21, an ordinary screw-driver may be used, or in fact, any other object capable of being used as a blade or key, as for instance, an ordinary coin—like a 85 quarter of a dollar. To release the side-rail requires but a retrograde movement of the screw sufficient to withdraw the cams from binding position upon the rail. As will be apparent, the rail may be reversed from the 90 position shown in the drawings, that is, with the horizontal web at the underside and disposed against the lower shoulder 15 of the socket. In such position, the vertical web lies against the adjacent face of the outer 95 vertical side-wall and the horizontal web extends across the socket with its edge lying against the inner or adjacent face of the companion side-wall, both cams then being in position to bind against the underside of the horizontal web. Which ever 100 position the side-rail be caused to assume it will be secured against movement by the upward binding of the cams thereagainst.

If desired, but one cam-arm may be employed, and such may be located at one side or intermediate the two side-walls 1 at any point; also any means may be employed for operating the cams—a simple wedge-key inserted between the bridge 19 and the back-wall 4 being available for the purpose.

When the side-rail is employed in the position in which it is shown in the drawings, that is, with the horizontal web uppermost, it will be seen that the same overlaps the inner end of the end-rail, so that the latter serves as a support for that side of the side-rail and when reversed, that is, with the web lowermost, the two cams 18 operate to bind against the same at its underside, the shoulder 28 underlapping the shoulder 15 of the socket. In either position, therefore, of the side-rail, torsional strain is resisted successfully.

It will be observed that the opening 8 in 125 the side-wall 1 of the socket is slightly narrower than the horizontal web 10 of the cross or end-rail 9, and that the edge of said horizontal web is notched as at 29. This notch, when the rail is in position, engages 130

with the edge of the opening 8, forming an interlocking joint which aids in securing the rail rigidly in position. By slightly turning the rail when it is entered through the opening 8 and then straightening the rail to its proper position, the interlocking of the parts occur, after which the rail may be riveted to the lug or ear 7.

The doubled rear wall, while desirable, is 10 not necessary. It is readily formed by bending the rear portions of the blank forming the side-walls inwardly at an angle to the remaining portions, that of the one overlapping the other. When present considerable 15 additional strength is added to the socket.

It will be seen that regardless of which of the two positions the side-rail is caused to occupy, the vertical web thereof will lie along- 20 side the adjacent side-wall, the upper edge alongside the top or connecting-wall and the outer horizontal edge will lie alongside the companion side-wall; and therefore, that the rail will have at all times three points of 25 longitudinal contact with the walls of the socket.

Having described my invention, what I claim, is:

1. In a corner-lock for bedsteads, the combination with a rail, angular in cross-section, of a socket adapted to receive the same endwise, in either of two positions, said socket comprising opposite vertical side and top connecting-walls conforming to the webs of 35 the rail, and a cam located under the rail and within the socket, said cam being adapted to bind against the lower edge of the vertical web of the rail when the latter is in one position and against the under- 40 side of the horizontal web when it occupies the other position.

2. In a corner-lock for bedsteads, the combination with a rail, angular in cross-section, of a socket adapted to receive the same 45 endwise in either of its two positions, said socket comprising opposite substantially parallel side-walls and a top connecting- wall, and a rocking cam located under the rail and within the socket and adapted to 50 bind upwardly against the rail and clamp the same against the top connecting-wall when said rail is in either of its said two positions.

3. In a corner-lock for bedsteads, the combination with a rail angular in cross-section, of a socket adapted to receive the same 55 endwise, said socket comprising opposite parallel side-walls and a transverse top connecting-wall, a cam-lever pivoted within the 60 socket and below the rail and provided at its upper end with a cam-face adapted to bind against the rail and clamp the same against the underside of the top connecting-wall, and a screw threaded in an aperture formed 65 in the cam-lever at an angle to the pivots

thereof and adapted to adjust and secure the cam-lever to and in its binding position.

4. In a corner-lock for bedsteads, the combination with a rail, angular in cross-section, of a socket adapted to receive the same 70 endwise, said socket comprising opposite parallel side-walls and a top connecting-wall, a transverse pintle connecting the side-walls, a pair of levers fulcrumed on the pintle and having cam-faces at their upper 75 ends adapted to bind against the rail and clamp the same against the underside of the top connecting-wall of the socket, means for adjusting said levers in unison, and means for locking said levers when adjusted. 80

5. In a corner lock for bedsteads, the combination with a rail, angular in cross-section, of a socket adapted to receive the same endwise, said socket comprising opposite parallel side-walls and a top connect- 85 ing wall, a transverse pintle connecting the side-walls, a pair of correspondingly shaped levers fulcrumed on the pintle and having corresponding cam-faces at their upper ends, one of the cam-faces being adapted to 90 bind against the lower edge of the vertical web of the rail when the latter is in one position and the two cam-faces being adapted to bind against the underside of the horizontal web of the rail when the latter is in 95 its other position, means for adjusting said levers in unison, and means for locking said levers when so adjusted.

6. In a corner-lock for bedsteads, the combination with a rail, angular in cross- 100 section, of a socket adapted to receive the same endwise, said socket comprising op- 105 posite parallel side-walls and a top connect- ing-wall, a transverse pintle connecting the side-walls, a pair of levers fulcrumed on the pintle and having cam-faces at their upper ends adapted to bind against the rail and clamp the same against the top connect- 110 ing-wall of the socket, a transverse bridge- piece connecting the levers, and an adjust- ing-means carried by the bridge-piece.

7. In a corner-lock for bedsteads, the combination with a rail, angular in cross-section, of a socket adapted to receive the same endwise, said socket comprising op- 115 posite parallel side-walls and a top connect- ing-wall, a transverse pintle connecting the side-walls, a pair of levers fulcrumed on the pintle and having cam-faces at their upper ends adapted to bind against the rail and clamp the same against the top connect- 120 ing-wall of the socket, a transverse bridge- piece connecting the levers, and an adjust- ing screw mounted in the bridge-piece.

8. In a corner-lock for bedsteads, the combination with a rail, angular in cross-section, of a socket for receiving the same and comprising one vertical and one lateral or top wall, the latter wall terminating in a vertical abutment at its free edge opposite 130

the vertical wall, the walls of the socket being disposed in the same angular relation to each other as are the webs of the rail and therefore conforming thereto, and a pivoted cam-faced locking-device located in the socket and adapted to bind against the lower edge of the depending flange of said rail when in position and clamp the upper flange or web of the rail against the lateral wall of the socket between said vertical wall and abutment.

9. In a corner-lock for bedsteads, the combination with a rail, angular in cross-section, of a socket adapted to receive the same endwise, said socket comprising opposite parallel side-walls and a top connecting-wall, a transverse pindle connecting the side-walls, a pair of levers fulcrumed on the pindle and having cam-faces at their upper ends adapted to bind against the rail and clamp the same against the top connecting-wall of the socket, a transverse bridge-piece connecting the levers and intermediate the same having an opening, an adjusting-screw mounted loosely in the opening and terminating in a counter sink in the rear wall of the socket, and a nut threaded on the screw in rear of the bridge-piece and between the levers.

10. In a corner-lock for bedsteads, the combination with a rail, angular in cross-section, of a socket for receiving the same in either of its two positions and comprising one vertical and one lateral wall, said walls being disposed in the same relation to each other as are the webs of the rail and therefore conforming thereto, and a pivoted cam-faced locking-device located in the socket and adapted to bind said rail against one of said walls when said rail is in either of its said two positions.

11. In a corner-lock for bedsteads, the combination with a rail, angular in cross-section, of a socket for receiving the same and comprising a vertical and a lateral wall disposed in the same relation to each other as are the webs of the rail and therefore conforming thereto and adapted to receive said rail, a cam adapted to bind against the lower edge of the depending flange of the rail for locking the rail within the socket, and a supporting-means carried within the socket and adapted to engage under the opposite free edge of the horizontally disposed web of said rail.

12. In a corner-lock for bedsteads, the combination with a rail, angular in cross-section, of a socket for receiving the same in either of its two positions, said socket comprising a horizontal and a vertical wall, said walls being arranged in the same relation to each other as are the webs of the rail and therefore conforming thereto, and a pivoted cam-faced locking-device located in the socket and adapted to bind said rail

against the horizontal wall of the socket when said rail is in either of its two positions.

13. In a corner-lock for bedsteads, the combination with a rail, angular in cross-section and having its opposite webs reduced near its ends, of a socket, comprising opposite substantially parallel walls and a top connecting wall, said socket being adapted to receive the reduced end of the rail and having its inner wall provided with an extension forming upper and lower shoulders adapted to interlock with the webs of the rail beyond the reduced portions thereof, and means for locking the rail within the socket.

14. In a corner-lock for bedsteads, the combination with a rail, angular in cross-section and having its horizontal web uppermost and reduced near its ends, of a socket adapted to receive said reduced end of the rail and comprising opposite substantially parallel walls and a top connecting-wall, the innermost of said parallel walls having a shoulder beyond its front edge below the plane of the horizontal web of the rail and supporting said web beyond its reduced portion, and means for locking the rail within the socket.

15. In a corner-lock for bedsteads, the combination with a rail, angular in cross-section, of a socket adapted to receive the same and comprising opposite substantially parallel side-walls and a top connecting-wall, the innermost of said side-walls having an opening immediately below the top-wall and at one side the same a laterally disposed lug, an end-rail riveted to the lug and extending through and beyond the opening into the socket and under the horizontal web of the first-mentioned rail and thereby aiding in the support of the same, and means for locking the first-mentioned rail in the socket.

16. In a corner-lock for bedsteads, the combination of a sheet-metal socket, angular in cross-section and adapted to receive endwise the angular side-rail, said socket comprising a pair of opposite vertical side-walls and an upper transverse connecting-wall, one of said side walls at its front edge and below the plane of the transverse wall being provided with a web-supporting shoulder, with an angular rail of a normal width exceeding that of the socket and having its end reduced to enter the socket endwise, the transverse portion of said rail in front of the socket being wider than the same and resting at its outer free edge upon said supporting-shoulder of the socket, and means for securing the rail in position within the socket.

17. In a corner-lock for bedsteads, the combination of a sheet-metal socket, angular in cross-section and adapted to receive end-

wise the angular side-rail, said socket comprising a pair of opposite vertical side-walls and an upper transverse connecting-wall, one of said side-walls at its front edge and below the plane of the transverse wall being provided with upper and lower web-supporting shoulders, with an angular rail of a normal width exceeding that of the socket and having its end reduced to enter the 5 socket endwise, the transverse portion of said rail, in front of the socket, being adapted to overlap and rest against the upper or lower shoulders of the side-wall, in accordance with the position of the rail, and 10 means for securing the rail in position within the socket.

18. In a corner-lock for bedsteads, the combination of a sheet-metal socket, angular in cross-section and adapted to receive endwise the angular side-rail, said socket comprising a pair of opposite vertical side-walls and an upper transverse connecting-wall, one of said side-walls being provided with a lower web-supporting shoulder, with an 20 angular rail of normal width exceeding that of the socket and having its end reduced to enter the socket endwise, the lower transverse web of said rail, in front of the socket, at its outer free edge overlapping the web-supporting shoulder of the side-wall, and 25 means for supporting the rail in position with its web against said shoulder.

19. In a corner-lock for bedsteads, the combination with a side-rail, angular in 30 cross-section, of a socket adapted to receive the same and comprising opposite substantially parallel side-walls and a top connecting wall, the innermost of said side-walls

having an opening immediately below the top-wall and at one side the same a laterally 40 disposed lug, an angular end-rail riveted to the lug and having its horizontal web wider than the opening, inserted through and beyond the same and notched to interlock with the edge thereof and extending 45 under the horizontal web of the side-rail, and means for locking the side-rail within the socket.

20. A bed-rail fastener of the character described, comprising a housing, means for 50 attaching said housing to a bed-post, and means for reversibly attaching an angle-iron side-rail to said housing, said means including a cam pivotally carried by said housing and adapted to exert pressure 55 directly upon the surface of a flange of the side-rail.

21. A bed-rail fastener of the character described comprising a housing, means for attaching said housing to a bed-post and 60 means for reversibly attaching an angle-iron side-rail to said housing, said latter means including a cam pivotally carried by said housing and adapted to exert pressure 65 directly upon either of the flanges of said side-rail and bind the side-rail against that wall of the housing opposite which the working face of the cam is located.

In testimony whereof I have signed my 70 name to this specification in the presence of two subscribing witnesses.
